UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,279,812.

Specification of Letters Patent. Patented Sept. 24, 1918.

Application filed July 14, 1917. Serial No. 180,632.

To all whom it may concern:

Be it known that I, SAMUEL B. WILLIAMS, Jr., a citizen of the United States, residing at Brooklyn, in the county of Kings and 5 State of New York, have invented certain new and useful Improvements in Telephone-Exchange Systems, of which the following is a full, clear, concise, and exact description.

10 This invention relates to a call distributing system for telephone exchange systems, and more particularly to a system of this character in which calling lines are extended to call receiving units by means of automatic switching apparatus.

15 The call receiving units may be the apparatus associated with an operator's position or they may be connecting circuits of an automatic telephone system which include 20 selector switches adapted to be controlled by the calling subscriber in establishing a connection.

In accordance with a feature of the invention, a plurality of line finding switches are 25 provided, each having access to a large number of lines. These lines are arranged in small groups in the finder switches and such finder switches are directed to the particular group including a calling line by means of 30 apparatus common to a plurality of such small groups. More specifically the lines are divided into groups of one hundred and a plurality of finder switches are provided having access to said groups. The groups 35 of one hundred lines are connected in subgroups of ten in the finder switches. A pair of distributor switches and a corresponding pair of switches of the type known in the art as line switches, are employed for the 40 purpose of directing the finder switches to the subgroups including the calling line. By virtue of this arrangement in finding any calling lines it is only necessary for the finder switch to hunt in the small subgroup.

45 In the embodiment of the invention disclosed the distributors are of the type shown in the applicant's pending application, Serial No. 144,069, renewed January 23, 1917. The line switches are of the type shown in 50 the United States Patent 1,078,685 to A. E. Keith.

In the drawings Figures 1 and 2 diagrammatically represent the apparatus individual to a group of one hundred lines and

55 Fig. 3 is a diagram showing the arrange-

ment of the distributor contacts. There are provided for each fifty lines, two distributors such as indicated in Fig. 3. These distributors are provided with five groups of ten line contacts, such as 16, 17 and 18. There 60 is also provided for each group of ten lines a pair of contacts 19 and 20, and a long contact 21. A rotatable arm 22 carries five brushes 11, 12, 13, 14 and 15 which coöperate with these contacts. The arm is adapted to 65 be rotated through a pawl and ratchet mechanism from a motor magnet 10 which is intermittently actuated at certain times by an interrupter.

There are also provided for each group of 70 one hundred lines two line switches A and B, one of which is individual to each distributor. These line switches are of the general type shown in United States Patent 1,078,685, and are adapted to be operated 75 from the contacts of the corresponding distributor in the following manner: As shown in Fig. 1 each group contact 20 is connected to a contact 23 of the corresponding line switch. There are five of these contacts corresponding to the five groups individual to the distributor. When the brush 15 of the distributor rests upon the contact 20, provided no call has been registered in the group over which the brushes have just 80 passed; a circuit is established for the magnet 24, which in turn closes a circuit for the magnet 75, causing the plunger arms 26 to be moved back and forth in front of the stationary terminals indicated at 27. Also, 85 if no calls are received in the group of ten lines when the brushes carried by the distributor arm reach the pair of contacts 19 and 20, individual to the group, the power magnet 10 will be energized over a circuit 90 which extends from battery through the interrupter, magnet 10, brush 14, contact 19, back contact and outer left-hand armature of the relay 3, back contact and left-hand armature of relay 7 to ground. The arm 95 100 will, therefore, be stepped forward and the brush 14 will be carried into contact with the contact 21, through which a circuit will be maintained for the power magnet 10 direct to ground, so that the arm will continue 105 to step forward until the contacts 19 and 20 of the next group are reached and if no call has been initiated during the time that the brushes 11, 12 and 13 are passing over the contacts 16, 17 and 18 individual to that 110

group of ten lines, the arm of the distributor will continue to be stepped forward. As the magnet 24 is energized each time, the brush 15 makes contact with the contact 20 and 5 the arms 26 of the line switch A will be stepped back and forth over the contacts 27. For each group of one hundred lines there is provided a set of trunks or connecting circuits, one of which is shown in Fig. 2, 10 and individual to each of these trunks and having access to the terminals of the group of one hundred lines is an ordinary selector or finder switch of the type known as the up-and-around type. As will more clearly 15 appear from a description of the operation of the system, these finder switches are controlled in their first operation from the line switches and consequently from the distributors.

20 Common to the two line switches and hence to the group of one hundred lines is an interrupter indicated in general at 29, which consists of a constantly driven shaft 90, which carries a series of ten interrupters 25 Nos. 1 to 10, and a pick-up interrupter which, for the sake of convenience is shown on Fig. 2 and is indicated at 108. Inasmuch as the arms 26 of both line switches reverse their direction for each complete revolution 30 of the corresponding distributor, and inasmuch as the particular set of contacts 27 which are operated by said arms 26 as will presently be described, determines which of the interrupters shall be made operative to 35 control the setting of the finder switch, means are provided to automatically change the interrupter connections when the line switches change their direction of motion. This is done by means of the relays 30, 31, 40 30^a and 31^a. The relays 30 and 31 are adapted to be operated by means of a pair of contacts 32, which in turn is controlled by a cam 33 on the line switch, the arrangement being such that for one half revolution of 45 cam 33 while the arms 26 are being moved in one direction, the contacts 32 are closed, while for the other half revolution, the contacts 32 are open. By virtue of this arrangement, if the plunger arm 26 is, for example, 50 plunged into the first set of contacts 27, either the No. 6 or No. 10 interrupter is connected to the impulse lead 34, depending upon whether the relay 31 is energized or not. There is also provided individual to 55 each group of fifty lines and each distributor and line switch, a set of relays indicated at 3, 4, 5 and 6, a similar set of relays for the line switch B being indicated at 3^b, 4^b, 5^b and 6^b. It is thought that the 60 general arrangement of the apparatus has been sufficiently described so that the general operation of the system which will now be described may be understood.

For purposes of illustration, it will be 65 assumed that the subscriber's line shown in

Fig. 1 is a line in the sixth subgroup of ten of a group of one hundred lines; therefore, the terminals of this line are connected in the sixth level of all of the finder switches having access to that group of one hundred 70 lines. Also the terminals of this line appear in the first group of ten in the distributor.

As long as there are no calls initiated in the group of fifty lines apportioned to the distributor shown the operation is as follows:

The arm 22 of the distributor is continuously rotated by the power magnet 10, which magnet is alternately energized in the following circuits: from battery, through 80 the interrupter, magnet 10, brush 14, contact 21 (Fig. 3) to ground, or from battery through the interrupter, magnet 10, brush 14, contact 19, contact and outer left-hand armature of relay 3, back contact and left-hand armature of relay 7 to ground. Each time the brush 15 makes contact with the contact 20, which occurs five times per revolution of the distributor, the following circuit is established from battery, magnet 24, 90 arm 37, contact 23, contact 20, brush 15, contact and outer right-hand armature of relay 3, back contact and outer left-hand armature of relay 6 to ground. The relay 38 is energized in parallel with the magnet 95 24 in this circuit and at its armature and contact connects a ground to the circuit through the contact 40 and arm 39, thus insuring the complete operation of magnet 24. The magnet 24 releases the sector 42 and 100 closes the contacts 41, establishing a circuit from battery, magnet 75, contacts 45, contacts 41, to ground. The magnet 75, when operated in this circuit, opens the contacts 45 and steps the ratchet wheel 43 one step. 105 It is thought that it will now be apparent that as long as no calls are initiated the arms of the line switch will be moved back and forth, completing a cycle of movement for each two revolutions of the corresponding 110 distributor.

As the distributor rotates the brush 13 makes contact with the sleeve contacts 18 of the lines, and consequently the relay 2 is energized over the following circuit from 115 battery, relay 2, brush 13, contact 18, resistance 35 to ground, provided the particular line is not in use. If the line is in use as will presently appear, the relay 2 will not operate, as such relay will be 120 shunted by the low resistance 136 of the finder switch utilized in establishing the connection to such line. It being assumed that a call is initiated on the line shown in Fig. 1 when the brush 14 of the distributor 125 reaches the contact 21 individual to the particular group including the calling line, the distributor arm continues to be rotated until the brushes 12, 13 and 14 reach the set of contacts 16, 17 and 18 individual to the 130

calling line. As the brush 13 reaches the contact 18 of this line, a circuit is established for the relay 2, which circuit extends from battery through the relay 2, brush 13, contact 18, resistance 35 to ground. The energization of the relay 2 connects the relay 1 to the brushes 11 and 12, and since the brushes 11 and 12 are in contact with the contacts 16 and 17 individual to the calling line, the relay 1 will be energized over the subscriber's line circuit which is at this time closed at the switch hook at the calling subscriber's station. The energization of the line relay 1 is only momentary. It should be remembered, however, that, as the calling line is included in the sixth subgroup of one hundred lines, before the brush 14 makes contact with the segment 21 of the sixth group, in passing over the contact 20 of the preceding group, in the case assumed, the tenth group, the line switch arms 26 were moved to the position shown in front of the first group of contacts 27, or in other words in front of the group of contacts 27 which are connected to the No. 6 interrupter, as the springs 32 are maintained open, when the line switch arms are moved in the direction assumed.

The line relay 1 when energized closes a circuit for the relay 3 which extends from battery through relay 3 to the armature and contact of relay 1. The relay 3 closes at its inner left-hand armature a locking circuit for itself through the back contact of the relay 4. At its outer left-hand armature, the relay 3 disconnects ground from the contact 19 and therefore when the brushes 14 and 15 reach the contacts 19 and 20 at the end of the group, no circuit will be found for the power magnet 10, and the distributor arm will be stopped. This being the case, any other calls initiated in the same group of fifty lines will be without effect and cannot interfere with the call which is being established. At its outer right-hand armature the relay 3 disconnects ground from the brush 15 so that there will be no circuit for the magnet 24 of the line switch and so that the line switch will also stop.

At its inner-right-hand armature, the relay 3 closes a circuit for the relay 5 and 6 in series, which circuit extends from grounded battery through the left-hand armature and contact of relay 8, right-hand armature and contact of the relay 7, normal contacts of the relay 6, left-hand winding of the relay 5, inner right-hand armature and contact of relay 3 to ground. The relay 5 at its right-hand armature closes a temporary locking circuit for itself independent of the relay 3 and at its left-hand armature closes a circuit for the relay 4, which being energized opens the locking circuit for the relay 3. The relay 6 in operating through its armatures and

contacts closes a locking circuit for itself independent of the relay 5; through the relay 7 and opening its normal left-hand contact releases the relay 5. Therefore, the relays 3, 4, 5 and 6 operate in quick succession and all but the relay 6 are almost immediately released. The locking circuit for relay 6 extends from battery, left-hand armature and contact of relay 8, relay 7, right-hand armature and front contact of relay 6, relay 6, front contact and left-hand armature of relay 6 to ground. The relay 7 opens at its right-hand armature the original energizing circuit for the relay 6 and also for the relay 6^b.

As soon as the relay 6 is operated, and consequently the relay 7, a circuit is closed for the relay 100. This circuit extends from battery, through the relay 100, contact 109 thereof, side-switch arm 110 in position 1, side-switch arm 111 in position 1, back contact and inner armature of the magnet 106, conductor 112, front contact and left-hand armature of relay 7, to ground. The relay 100 at its inner right-hand armature and contact closes a locking circuit for itself which extends from battery, through the relay 100, contact 109 and inner right-hand armature of relay 100, side-switch arm 113 in position 1, right-hand armature and contact of relay 101, to ground. At its middle right-hand armature and contact the relay 100 closes a circuit for the pick-up relay 102, which circuit is closed through pick-up interrupter 108 just before the interrupter shaft 90 reaches a position, in which the first conducting segments of the other interrupters carried by such shaft 90 become operative. When this occurs the pick-up relay 102 is operated from a circuit which extends from ground, through the pick-up interrupter 108, middle right-hand armature and contact of relay 100, normal contact of relay 102, winding of relay 102 to grounded battery. As soon as the relay 102 is thus operated, the impulse circuit from the interrupter to the vertical magnet 104 of the finder switch individual to the connecting circuit allotted for use is established. This operation of the pick-up relay, however, may take place simultaneously with the operation of the plunger magnet 9 but cannot take place before the actuation of the plunger magnet because such plunger magnet is actuated over a circuit closed at the outer left-hand armature and contact of relay 100. This circuit extends from battery, through the plunger magnet 9, conductor 114, outer left-hand armature and contact of relay 100, conductor 115, the outer left-hand armature and front contact of the relay 6 to ground. The actuation of the plunger magnet 9 operates the contacts 27, which in the case assumed connects the No. 6 interrupter in the following circuit: from battery, through the

vertical magnet 104, slow release relay 103, side-switch arm 116 in position 1, the left-hand armature and contact of the pick-up relay 102, conductor 117, contact 27, conductor 34, right-hand armature and contact of relay 31, through the No. 6 interrupter, to ground. As before explained, this circuit can only be established when the brush of a No. 6 interrupter is about to encounter the 10 first conducting segment thereof due to the operation of the pick-up relay, so that the magnets of relays 104 and 103 will be energized in this circuit, and as the interrupter shaft revolves this circuit will be interrupted 15 six times, followed by a longer interruption as the interrupter revolves. Upon the first establishment of this circuit, the relay 103 being actuated, a circuit is closed for the side-switch magnet 105, which circuit extends 20 from battery, through magnet 105, side-switch arm 118 in position 1, contact and armature of the relay 103, to ground. The side switch, however, is arranged to stop only on release of the side-switch magnet. For each break of the circuit just 25 traced for vertical magnet 104 and the relay 103, the vertical magnet 104 is deenergized but the relay 103 will remain energized. The brush shaft is, therefore, stepped up 30 to the sixth level, in which level, in the case assumed, the desired line is to be found. After the sixth operation of the stepping magnet 104, the circuit is opened at the interrupter sufficiently long to permit the slow 35 release relay 103 to release, thus opening the circuit of the side-switch magnet 105, and causing the side switch to move into position 2.

Before proceeding further with the effect 40 on the finder switch of the movement of the side switch into position 2, the effect of this operation in releasing the apparatus previously used in directing the finder switch to the sixth level will be described. When the 45 side-switch arm 113 moves into position 2, the locking circuit for both the relays 100 and 102 is opened at the side-switch arm 113, causing both of these relays to release. The release of the relay 100 releases the plunger 50 magnet 9, and as the line switch A has not been moved, the plunger 26 will immediately reengage the shaft of the line switch. As soon as the finder switch made the first vertical step, the off-normal contact 119 was 55 closed, so that when the relay 100 releases, the following circuit is established: from grounded battery, through the relay 8, conductor 121, arm 120, outer right-hand armature and contact of relay 100, off-normal 60 contact 119 to ground. The energization of the relay 8 in this circuit, opens the holding circuits for the relays 6 and 7 and restores them to normal. As soon as the relay 7 is released, it being remembered that the arm 22 65 stopped with the brush 14 on the contact 19,

due to the energization of the relay 3, and was prevented from leaving such contact when the relay 3 released, due to the energization of the relay 7 with both the relay 3 and the relay 7 released, a circuit is established 70 for the magnet 10 of the distributor, which extends from battery, through the interrupter, motor magnet 10, brush 14, contact 19, outer left-hand armature and back contact of the relay 3, back contact and left-hand armature of the relay 7, to ground. Therefore, the distributor again starts in motion and continues in motion and drives the line switch A until another call is initiated. 80

Immediately the relay 7 is released, due to the operation of the relay 8, the relay 8 at its right-hand armature establishes the following circuit for the motor magnet 106 of the allotter: from battery, through the 85 magnet 106, conductor 122, contact and right-hand armature of the relay 8, conductor 121, arm 120, outer right-hand armature and contact of the relay 100, off-normal contact 119 of the finder switch, to ground. 90 The relay 106 energized in this circuit closes a circuit for the power magnet 107 of the allotter, which extends from battery, through the interrupter, power magnet 107, outer armature and contact of the relay 106, to 95 ground. At its inner armature the relay 106 disconnects the conductor 112 from the allotter brush 111, in order to prevent the operation of the relays such as 100 associated with all the finder switches, in case a call 100 should come in on the particular group of fifty or any call lines terminating at the distributor shown. The relay 106 will be maintained energized as long as the arm 120 passes over contacts individual to the finder 105 switches which are in use, as the off-normal spring, such as 119 of all such finder switches will be operated to connect a ground to the corresponding allotter contacts. As soon as an idle finder switch is found, however, the relay 106 will release and open the circuit of the motor magnet 107 of the allotter, thus allotting the next idle finder switch for use in connection with the next 110 call initiated in either of the two groups of 115 fifty lines.

With the side switch in position 2, a circuit is closed for the rotary magnet 123 of the finder switch. This circuit extends from the interrupter, through the rotary magnet 120 123, side-switch arm 124 in position 2, left-hand armature and back contact of the relay 125, to ground. Also when the side-switch arm reaches position 2, a circuit is established for the side-switch magnet 105, 125 which extends from battery, side-switch arm 118 in position 2, back contact and armature of the test relay 126, to ground. Furthermore, in position 2 of the side switch, a circuit is prepared for the relay 127, side- 130

switch arm 128 in position 2, and through the brush 129. As the rotary magnet of the selector switch operates, the brushes 129, 130 and 131 are moved over the stationary terminals 132, 133 and 134. When the stationary terminals 134, individual to the lines, are encountered provided such lines are not connected to by other finder switches, the relay 127 is energized over a circuit 5 which extends from battery, the relay 127, side-switch arm 128 in position 2, brush 129, terminal 134, conductor 36, through the resistance 35, to ground. The operation of this relay 127 connects the test relay 126 across 10 the brushes 130, 131, and hence when the brushes 130, 131 reach the terminals 132, 133 individual to the calling line, the relay 126 is energized over a circuit which extends from battery, through the right-hand winding 15 of relay 126, inner armature and contact of the relay 127, brush 130, terminal 133, out over the subscriber's line, and back to the terminal 132, brush 131, outer armature and contact of the relay 127, left-hand 20 winding of the relay 126, to ground. The relay 126 when energized opens the energizing circuit for the side-switch magnet 105, causing the side switch to step to position 3, in which position the circuit of the rotary 25 magnet 123 is opened, and the finder switch 30 is stopped with the brushes thereof in connection with the calling line.

As soon as connection is established with the calling line the supervisory relay is included in circuit with the battery 137 and the transmitter of the calling line. The relay 135 operates the slow release relay 101 over a circuit from battery, relay 101, contact and armature of relay 135 to ground. 35 The relay 101 at its right-hand armature disables the release magnet 125 and at its left-hand armature connects the low resistance 136 to the sleeve or third conductor of the line, thus preventing the operation of 40 the relay 2 of the distributor and the relay 127 of other finders when they are connected to the terminals of such line in such distributor and finder switches. 45

Upon the termination of conversation, 50 when the calling subscriber hangs up, the relay 135 is deenergized, and consequently the relay 101 is released. The relay 101 when released, with the side switch in position 3, closes a circuit from battery, through 55 the release magnet 125, side-switch arm 113 in position 3, right-hand armature and contact of the relay 101, to ground. The operation of the release magnet restores the switch to normal.

60 Having traced the progress of one call from the time it was initiated until the time it was connected to a trunk, it is thought that the operation of the embodiment of the

invention disclosed will be sufficiently understood.

65

What is claimed is:

1. In a telephone exchange system, lines divided into main groups and subgroups, line finder switches having access to a plurality of main groups, means individual to each main group for successively testing all of the lines in a main group for calling lines, means responsive to a condition indicating a calling line for identifying the subgroup including such line, and means controlled by such identifying means for directing a finder switch to such identified subgroup and starting such finder switch to hunt in said subgroup for such calling line. 70

2. In a telephone exchange system, lines 80 arranged in main groups and subgroups, a plurality of finder switches each having access to a plurality of main groups, means individual to a main group for testing the lines of such main group in succession for calling lines, means responsive to a condition indicating a calling line in a subgroup to stop such testing means in a position to register a call in such subgroup, and means controlled by the position in which such 85 testing means is stopped to direct a finder switch to a group of terminals representing 90 said subgroup.

3. In telephone exchange system, lines divided into main groups and subgroups, finder switches each having access to a plurality of main groups, means individual to a main group for successively and continuously testing the lines of said main group for calling lines, means responsive to a condition indicating a calling line to temporarily stop said testing means to identify the subgroup containing such calling line, means controlled from such testing means in accordance with the position in which such 100 testing means is stopped for directing a finder switch to the terminals of the subgroup including the calling line, and means for starting said finder switch to hunt in the subgroup for the calling line and for simultaneously causing said testing means to resume its testing operation. 105

4. In a telephone exchange system comprising lines divided into groups and subgroups, line finder switches having access to 115 said main groups, motor magnets individual to said line finders adapted to respond to impulses to direct said line finders to the subgroups, a plurality of impulse senders, means independent of said line finders for 120 testing the lines of a main group in succession, and means controlled from said testing means for selectively associating the motor magnet of one of said line finders with one of such plurality of impulse senders to direct said line finder to a subgroup. 125

5. In a telephone exchange system, lines divided into main groups and subgroups, line finders having access to a plurality of said main groups, a testing switch arranged 5 to continuously and successively test the lines of a main group, means included in such testing switch responsive to the electrical condition on the terminals of a line indicating that a call has been initiated on 10 such line to stop said testing device, a switching device operated from said testing device in synchronism therewith, means for stopping said switching device when said testing device is stopped, a set of impulse 15 senders, and means controlled by said switching device for connecting one of such set of impulse senders to the motor magnet of a line finder to direct said line finder to a subgroup containing the calling line.
- 20 6. In a telephone exchange system, lines divided into main and subgroups, line finder switches having access to a plurality of said main groups, motor magnets for such line finders, a testing device for successively testing all of the lines of the main group, a 25 switching device controlled from such testing device including a plurality of plunger arms and sets of stationary contacts, a plurality of impulse senders, each arranged to 30 send a different series of impulses associated with said sets of stationary contacts, means controlled by the movement of the testing device in the testing operation thereof for moving said plunger arms back and forth in 35 front of the sets of stationary contacts, and means rendered operative when said testing device encounters a calling line in the main group to operate one of such plungers to cause it to operate one of the sets of contacts, 40 and means controlled by the operated set of contacts for directing a line finder switch to the subgroup containing the calling line.
- 45 7. In a telephone exchange system, lines divided into main groups and subgroups, line finder switches having access to a plurality of said main groups, a testing device adapted to continuously and successively test the lines of a main group for calling 50 lines, a line switch associated with said testing device, said line switch including a plurality of plungers and sets of contacts, there being a plunger on such line switch for each 55 line finder having access to the same main group of lines and a set of contacts for each sub-group of lines, means controlled by said testing device for moving said plungers back and forth in front of such sets of stationary contacts, impulse senders associated with said sets of contacts, means controlled from said testing device when a calling line is encountered to cause a plunger of said line switch to operate a set of stationary contacts individual to the subgroup containing the calling line, and means controlled through the operated set of contacts to connect an impulse sender adapted to send the proper number of impulses to direct the line finder individual to the plunger to the subgroup containing the calling line. 60 65
8. In a telephone exchange system, lines 70 divided into main groups of fifty and subgroups of ten, line finder switches having access to two main groups, a testing device adapted to successively test the fifty lines of a main group and a line switch provided 75 with a plunger for each line finder having access to the main group, means controlled from the testing device for operating said line switch to move the plungers thereof back and forth over sets of stationary contacts, there being a set of such contacts for 80 each group of ten lines of the main group of fifty to which the line switch is individual, an interrupter associated with each set of contacts, means included in said testing 85 device responsive to a condition on a line indicating that such line is calling for stopping said line switch and operating one of said plungers, means operated by said plunger for connecting one of said interrupters with the motor magnet of a line finder to direct 90 said line finder to the subgroup containing the calling line. 90
9. In a telephone exchange system, lines 95 divided into main groups and subgroups, a group of trunks, means individual to a trunk for connecting said trunk to any line in a plurality of main groups, testing means independent of said connecting means for successively testing the lines of a main group; 100 including means for identifying a subgroup containing a calling line, means for pre-selecting an idle trunk and placing the connecting means associated therewith under the control of the testing means, and means 105 individual to the subgroups identified by such testing means for directing such connecting means to such subgroup. 105
- In witness whereof, I hereunto subscribe my name this 13th day of July, A. D. 1917.
- SAMUEL B. WILLIAMS, JR.
